UNITED STATES PATENT OFFICE.

UTLEY WEDGE, OF ARDMORE, PENNSYLVANIA.

METALLURGICAL FURNACE.

1,115,263.

Specification of Letters Patent. Patented Oct. 27, 1914.

Application filed February 25, 1913. Serial No. 750,596.

To all whom it may concern:

Be it known that I, UTLEY WEDGE, a citizen of the United States, residing in Ardmore, Pennsylvania, have invented certain 5 Improvements in Metallurgical Furnaces, of which the following is a specification.

My invention relates to a furnace of the superposed hearth type having rabbles which are carried by and depend from the 10 hearths.

My invention relates particularly to a small furnace of this type intended for laboratory use, the objects of my invention being to so construct such a furnace as to 15 keep the cost of the same within reasonable limits, to minimize the height of the furnace considering the number of hearths therein, to provide simple and efficient means for carrying the hearths and for rotating such 20 of the same as have to be rotated; to provide for the ready insertion and removal of the rabbles; and to permit of the use of the furnace without discomfort in a closed room.

The objects I attain in the manner herein- 25 after set forth reference being had to the accompanying drawing which represents a vertical sectional view of a furnace constructed in accordance with my invention.

In the drawing, I have shown a furnace 30 having nine hearths numbered consecutively from top to bottom of the furnace, the hearths 1, 3, 5, 7, and 9 being fixed hearths mounted in the outer wall of the furnace and the hearths 2, 4, 6 and 8 being rotating 35 hearths which are carried by a central shaft 10 mounted in a suitable step bearing below the furnace and intended to be rotated by any suitable mechanism, preferably of such character that the speed of rotation of the 40 shaft can be changed at will. The furnace may, however, have a greater or less number of hearths than I have shown.

The shaft 10 is preferably hollow so as to permit of the circulation of a cooling 45 medium through it and it is surrounded by relatively short sleeve sections 11 interposed between the successive rotating hearths so as to aid in the support of the same, said sleeves being composed of fire brick, tile, or 50 other heat-resisting material, in order to protect the shaft from injury by the high temperatures which may have to be maintained within the working chambers of the furnace.

The outer wall of the furnace is composed of rings 12 of fire brick, tile, or other refractory material made either in one piece or in sections and interposed between the successive fixed hearths of the furnace whereby the building-up of a furnace structure having a closed casing can be effected expeditiously and with small expenditure of time and labor.

In order to restrict, as much as possible, the radiation of heat from the furnace, the outer wall of the same is provided with a coating or covering 13 of magnesia, asbestos cement, or other material which is a non-conductor or a poor conductor of heat.

The lowermost of the rotating hearths of 70 the furnace is mounted upon a flange or collar 14 on the shaft 10, and, where said shaft passes through the top and bottom fixed hearths, it is provided with luted joints 15 to prevent the escape of gas from the interior of the furnace at these points. The top hearth of the furnace may conveniently be used as a drying hearth, the material being fed inwardly over the same by means of rabbles 16 carried by rabble arms 17 secured 80 to and projecting from the upper portion of the shaft 10, the material being fed from the drying hearth 1 onto the first rotating hearth 2 through the upper luted joint 15 and the course of the material in its passage through the furnace being then outwardly on the rotating hearths and inwardly on the stationary hearths, the rotating hearths being less in diameter than the interior of the furnace and the stationary 90 hearths being provided with central openings 18 of greater diameter than the sleeves 11 in order to permit of the dropping of the material from hearth to hearth. In order to provide for such movement of the material 95 over the hearths rabbles are provided, these rabbles having stems supported in rabble holders which are mounted in openings in the fixed and rotating hearths and extend below the same so that the rabble stems can 100 be readily applied thereto, the rabbles of one hearth acting upon the material on the hearth below. The hearths may be so constructed that the direction of travel of the material over the same will be the reverse 105 of that just described without departing from any of the essential features of my invention.

The rotating hearths are, by preference, composed of rings of tile or other refractory material, either in one piece or in sections, and the stationary hearths may be composed of like rings.

It is also advisable to provide the casing of the furnace at both the uppermost and lowermost chambers thereof with a pipe or conduit for the introduction of air or the escape of the gases developed in the furnace, the use of such conduit at each end of the furnace providing for the operation of the latter with either updraft or downdraft.

When the rabbles are separate from the rabble holders, a rabble can be readily changed by withdrawing it horizontally from engagement with the rabble holder, removing it through a suitably located opening in the outer wall of the furnace, and inserting a fresh rabble in its place and the rabble holder, after the removal of the rabble, can be lifted from its seat in the hearth into the chamber above the hearth from which it can likewise be withdrawn and a new one inserted in its place, whereas, if the rabble and rabble holder was made in one piece this method of change could not be adopted and the furnace would have to be dismantled whenever it became necessary to change the rabbles.

In a furnace of the type to which my invention relates, a great number of hearths can be used without unduly increasing the height of the furnace because said hearths can be disposed relatively close together, no provision having to be made for the reception of rabble-carrying arms in the chambers between the hearths.

The rabble holders may project below the hearths, as shown for instance at 20 and 20^a, Fig. 1, so that the rabbles may be connected thereto by horizontally separable joints, as shown respectively at 19 and 19^a, or the joints may be vertically separable as shown for instance at 19^b and 20^b, Fig. 1, or the rabbles may be applied directly to the hearths in some cases, as shown for instance at 19^c, Fig. 1, and the term "depending from said hearths" is intended to apply either to the construction in which the rabbles are applied directly to the hearths or indirectly through the medium of the rabble holders.

The central shaft may be stationary and the outer casing rotatable if desired, or one may be rotated in one direction and the other in the opposite direction, but the construction which I have heretofore described is much to be preferred.

When vertically separable couplings are employed between the rabbles and rabble holders or hearths that portion of the rabble which enters the coupling is of lesser vertical dimensions than the distance between the bottom of the rabble and the hearth beneath so that the rabble may be first lowered

to clear the coupling and then withdrawn laterally from the chamber between the hearths, and the rabble holders 20^a are less in depth than the distance between the adjoining hearths to permit of vertical separation from the hearth below and subsequent lateral removal from between said hearth and the hearth above.

I claim:—

1. A metallurgical furnace having a central shaft and an outer casing, one rotatable in respect to the other, overlapping hearths carried respectively by said central shaft and outer casing, and rabbles depending from said hearths and serving to move the material over the same.

2. A metallurgical furnace having a central shaft and an outer casing, one rotatable in respect to the other, hearths mounted alternately upon said central shaft and outer casing, and rings of refractory material surrounding said shaft and interposed between the hearths carried thereby so as to protect the shaft from heat and also aid in the support of the hearths.

3. A metallurgical furnace having alternating fixed and rotating hearths, a central rotatable shaft on which said rotating hearths are mounted, and rings of refractory material surrounding said shaft and interposed between the rotating hearths.

4. A metallurgical furnace provided with an outer casing and a central shaft, one rotatable in respect to the other, hearths projecting inwardly from said outer casing, and hearths carried by and projecting outwardly from said central shaft and alternating with the other hearths, said outer casing being composed of rings of refractory material interposed between the hearths of said outer casing and serving to separate and support said hearths.

5. The combination, in a metallurgical furnace, of a series of superposed hearths some of which are rotatable in respect to the others, and rabbles depending from said hearths and separably coupled thereto, that portion of the rabble which enters the coupling being less in vertical dimensions than the distance between the bottom of the rabble and the hearth beneath.

6. The combination, in a metallurgical furnace, of alternating fixed and rotating hearths, with rabbles depending from said hearths, and rabble holders mounted in said hearths so as to be vertically removable therefrom, said rabble holders being of less depth than the space between the hearth which carries them and the hearth above it and being in separable connection with the rabbles.

7. The combination, in a metallurgical furnace of alternating fixed and rotating hearths, with rabbles depending from said hearths, and rabble holders mounted in said

hearts so as to be vertically removable therefrom, said rabble holders being less in depth than the space between the hearth which carries them and the hearth above it, and the 5 rabbles being so mounted in said holders as to be horizontally separable therefrom.

In testimony whereof, I have signed my

name to this specification, in the presence of two subscribing witnesses.

UTLEY WEDGE.
